REMOVABLE EAR PIECE FOR TELEPHONE INSTRUMENTS

Ernst Alden Eriksson, Westford Road,
Tyngsboro, Mass. 01879

Filed July 5, 1968, Ser. No. 12,643

Term of patent 14 years

Int. Cl. D14—01

U.S. Cl. D26—14

FIG. 1

FIG. 2

FIG. 3

FIG. 4

FIG. 5

FIG. 6

FIG. 1 is a top plan view of a removable ear piece for telephone instruments, showing my new design;
FIG. 2 is a rear view of the removable ear piece;
FIG. 3 is a front view of the removable ear piece;
FIG. 4 is a side view of the removable ear piece;
FIG. 5 is a bottom plan view of the removable ear piece, and

FIG. 6 is a perspective view of the removable ear piece.

I claim:

The ornamental design for a removable ear piece for telephone instruments, as shown.
